UNITED STATES PATENT OFFICE

159,662

PEDICURE APPLIANCE

Richard J. Patek, Los Angeles, Calif.

Application December 10, 1949, Serial No. 6,550

Term of patent 14 years

(Cl. D86—10)

To all whom it may concern:

Be it known that I, Richard J. Patek, a citizen of the United States of America, residing at 1836 Rotary Drive, Los Angeles 26, in the county of Los Angeles, State of California, have invented a new, original, and ornamental Design for a Pedicure Appliance, of which the following is a specification, reference being had to the accompanying drawing, forming a part hereof.

Figure 1 is a perspective view of a pedicure appliance showing my new design;

Figure 2 is a top edge view of the same;

Figure 3 is an end elevation thereof;

Figure 4 is a bottom edge view of the device; and

Figure 5 is a cross-section taken along the line 5—5 in Figure 1.

I claim:

The ornamental design for a pedicure appliance, as shown.

RICHARD J. PATEK.
